UNITED STATES PATENT OFFICE

JOHN JOSEPH WILLMOTT, OF MONTCLAIR, NEW JERSEY, ASSIGNOR TO LOUIS FARBER, OF YONKERS, NEW YORK

DESIGN FOR A HOLDER

Application filed April 15, 1932. Serial No. 43,499. Term of patent 7 years.

To all whom it may concern:

Be it known that I, JOHN JOSEPH WILLMOTT, a citizen of the United States, and resident of Montclair, in the county of Essex and State of New Jersey, have invented a certain new, original, and ornamental Design for a Holder, of which the following is a specification, reference being had to the accompanying drawing, forming part thereof.

In the drawing Fig. 1 represents an ornamental elevation of a holder for a decanter, a glass, a bottle or various other objects, showing my new design; Fig. 2 shows a top plan view of Fig. 1.

I claim:

The ornamental design for a holder as shown.

Signed at the borough of Manhattan, city of New York, in the county of New York and State of New York, this 25th day of March, A. D. 1932.

JOHN JOSEPH WILLMOTT.
